UNITED STATES PATENT OFFICE.

GEORGE CHAMBERS AND ROBERT J. STEWART, OF MOUNT CLEMENS,
MICHIGAN.

DESIGN FOR A SPOON OR SIMILAR ARTICLE.

No. 37,989.

Specification for Design.

Patented May 8, 1906.

Application filed April 7, 1906. Serial No. 310,580. Term of patent 14 years.

To all whom it may concern:

Be it known that we, GEORGE CHAMBERS and ROBERT J. STEWART, citizens of the United States of America, residing at Mount Clemens, in the county of Macomb and State of Michigan, have invented a new, original, and ornamental Design for Spoons or Similar Articles, of which the following is a specification, reference being had to the accompanying drawing, forming a part thereof, in

which the figure is a front elevation of a spoon, showing our new design.

We claim—

The ornamental design for a spoon or similar article, as shown.

GEORGE CHAMBERS.
ROBERT J. STEWART.
